ROTARY WING VTOL AIRCRAFT WITH TILT TABLE SECONDARY WING

Peter F. Girard, La Mesa, Calif., assignor to The Ryan
Aeronautical Co., San Diego, Calif.

Filed Apr. 12, 1965, Ser. No. 84,743

Term of patent 14 years

(Cl. D71—1)

Fig. 1

Fig. 2

Fig. 3

Fig. 4

Fig. 5

Fig. 6

Fig. 7

FIGURE 1 is a perspective view of a rotary wing VTOL aircraft with tiltable secondary wing, showing my new design, the aircraft being illustrated in cruising flight configuration;

FIGURE 2 is a similar perspective view, but with the aircraft in vertical flight configuration;

FIGURE 3 is a left side elevational view of the aircraft;

FIGURE 4 is a bottom plan view thereof;

FIGURE 5 is a front elevational view thereof;

FIGURE 6 is a rear elevational view thereof; and

FIGURE 7 is a right side elevational view with the aircraft in vertical flight configuration.

I claim:

The ornamental design for a rotary wing VTOL aircraft with tiltable secondary wing, as shown and described.
